MULTIRANGE TUNER FOR ULTRA HIGH FREQUENCY TRANSMITTERS

John Mathieson Dodds, Timperley, and John Heywood Ludlow, Bowdon, England

Application December 29, 1943, Serial No. 516,104
In Great Britain May 13, 1938

13 Claims. (Cl. 250—40)

1

This invention relates to radio transmitters of the kind in which provision is made for changing expeditiously the wavelength of transmission by the substitution of different tuning inductances the one for another. Such arrangements are mostly employed in transmitters operating on relatively short wavelengths such as in the range of from 13 to 70 metres which is used for "beam" working wherein owing to changes in conditions of propagation an alteration of wavelength is usually to be effected frequently in order to ensure reasonable continuity of service.

In general, the wave changing arrangements comprise a number of inductances or tuned circuits mounted upon a rotating structure or turn-table each inductance being provided with switch contacts so that any one of the inductances or tuned circuits can be connected to the associated power valve or valves. Such arrangement permits the change to be made in a relatively short time. Since on beam stations a separate aerial array is used for each wavelength, a selector switch has also to be operated to connect the appropriate feeder lines to the transmitter. In the use of such a rapid wave changing arrangement, having rotated the turntable to substitute one inductance or tuned circuit for another, the operator then sets the various variable tuning condensers to predetermined positions or values and causes the power to be applied, a final adjustment of the tuning condensers being usually necessary.

In our application Ser. No. 516,103 for Radio transmitters, filed December 29, 1943, wave changing arrangements are described involving switch arms for selectively connecting a plurality of fixed inductances to terminals of push-pull valves. It will be appreciated that in spite of the dimensioning and arrangement set forth in that application, owing to the finite inductance of the switch arms and the displacement of the inductance coils laterally from the valves, the minimum possible wavelength at which the valves can efficiently operate is not achieved. The present invention is based on the consideration that when it is desired to resonate the valves to the minimum wavelength which can be achieved without recourse to series condensers, a satisfactory performance can be obtained when the inductance comprises a short straight wide bar connected directly between the electrode terminals and electrically weld joined to the latter. The inductance loop then comprises the bar and the electrode terminals of the two valves, the electrodes themselves and the supports of

the electrodes. Such loop can satisfactorily be used for feeding in or feeding out high frequency energy by magnetic or other coupling means.

Regarding the mention in the preceding paragraph of the use of a series condenser, in many circuits when high power is handled at relatively high voltages, the series condenser if used effectively must have the same order of capacity as that between the valve electrodes. It will be appreciated therefore that the use of such a series condenser becomes difficult owing to the high voltage developed across it, particularly in an anode circuit. If the condenser is of the air dielectric type it is inherently of large size in order to withstand the voltage and this fact, coupled with its high inherent inductance, is considered to outweigh the advantage otherwise derived from the use of such condenser. On the other hand other types of condenser than air dielectric condensers are generally found to be unsatisfactory on the very short wavelengths in question.

The object of the present invention is a rapid wave changing arrangement which permits the minimum possible wavelength to be achieved. As hereinbefore indicated the free radial length of the switch blades set forth in said application Serial No. 516,103 cannot be made less than the clearance required between the pairs of contacts or jaws to which the respective inductances are attached and between such adjacent parts as are alive when the switch is in another position to that which it occupies when in position to connect the selected inductance to the electrodes.

According to the present invention the improved inductance wave changing arrangements comprise the electrode terminal member of a valve which terminal member has a switch contact face, an inductance terminal member having a contact face preferably parallel with the face of the electrode terminal member and spaced apart only a sufficient distance safely to withstand the working voltage stresses between said faces, and a movable contact blade or bridge having two opposite contact faces adapted to engage between the aforesaid two contact faces. The fixed terminal member of the inductance has or is adapted to have secured to it an inductance which for the minimum possible wavelength is a straight

wide bar, that is to say wide in the direction par-

allel with the axis of the inductance loop formed thereby. The electrode terminal member may have a plurality of contact faces or alternatively it may have an extended contact face. Adjacent said other contact face or another part of the extended contact face may be arranged a further fixed inductance terminal member, so that by moving said bridge from one position to another or employing two alternatively operable bridges, the value of the inductance may be varied, the second or the further inductances having for instance a semicircular loop, a complete turn, or more than one complete turn. Preferably the arrangement set forth is duplicated, that is to say there is a bridge or blade member on each side of the inductance, the arrangement being symmetrical with respect to the inductance extended horizontally between two push-pull valves arranged side-by-side. The valves are preferably in accordance with British Letters Patent No. 414,753 or No. 458,702 or No. 497,359.

In carrying out the invention the adjacent contact faces may be made plane and parallel. The two bridge or blade contacts may be moved simultaneously by suitable insulated arms or levers.

In an arrangement which is alternative or additional to employing a plurality of fixed inductances of different value in the arrangement above set forth one or more of the inductances may be variable and comprise a pair of parallel bars, with which the bridge or blade members are adapted to make contact as hereinbefore stated, whilst a transverse inductance bar or bridge is slidably arranged between said parallel bars so that the inductance value can be changed as desired.

The invention above set forth may be combined with the invention forming the subject of the above mentioned application Serial No. 516,103 filed of even date herewith, by using the aforesaid bridges or arms in conjunction with the switch jaws or the equivalent to which a plurality of fixed inductances are attached in the manner described in that application, the arrangement being such that the straight inductance bar (or adjustable bridge) can be used when desired for operation on the minimum wavelength. The blade may be wide in the axial direction throughout its length although its width is actually only required to obtain the requisite voltage clearances as hereinbefore mentioned in the minimum wave position.

The invention also comprises the following further subsidiary feature when applied more particularly to anode circuits. The general difference between the anode terminal of a high power valve and the terminal of the other electrodes is that the anode terminal usually has considerably greater axial length, at least in the case of fluid cooled valves of the metal envelope type. It will thus be appreciated that a straight bar type of inductance may be connected directly between the anodes of a pair of valves at any level within the lengths of the anodes. The position of the bar for minimum wavelength would be at the end of the anodes nearest to the terminals of the electrodes with which the anodes are being resonated. A particular advantage in this connection arises from the fact that the length of the switch bar or blade is of the same order as that of the axial length of the anode. Therefore according to this feature of the invention the hinge of the bridge or blade may be arranged at that end of the anode which is remote from the position for

minimum wavelength as just above mentioned. Thus the switch blade may in one position be closed along the length of the anode so that in this position it makes contact with a contact face of the anode in a position remote from the hinge, whilst simultaneously in this position making contact with an inductance terminal to which may be connected the straight bar. In other positions of the blade other inductances may be connected to the electrodes.

To enable the invention to be clearly understood certain considerations leading thereto and certain arrangements thereof by way of example will now be described with reference to the accompanying drawings in which:

Figure 1 is a simplified diagram illustrating the fundamental principle of the present invention.

Figure 2 is a similar diagram showing one embodiment of the present invention.

Figures 3 and 4 are front and side elevations of a more practical form of the invention, and

Figure 5 is a plan view of a modification of the invention, and

Figures 6 and 7 are an elevation and plan respectively of a further modification of the invention.

Referring first to Fig. 1 of the accompanying drawings it is to be assumed that, as hereinbefore set forth, two similar valves in accordance with British Letters Patent No. 414,753 are operated in push-pull and the anode circuit is resonated to the effectively earthed screening grids. Figs. 1 and 2 which are purely diagrammatic and from which various details are omitted show more clearly the basic circuit involved in accordance with the present invention. The symbols 1 represent the anodes, and 2 the screening grids of a pair of valves operated in push-pull. Each anode is supported on an insulating envelope portion 3 and the terminal 4 of each screening grid is led out annularly and is effectively connected, so far as the high frequency currents are concerned, to earth as represented at 5.

Each anode has of necessity a considerable external length, it being assumed that the anode is water-cooled and itself constitutes a portion of the evacuated envelope of the valve, which latter will probably be continuously evacuated during operation as described in British Letters Patent No. 414,753 aforesaid.

The shortest wavelengths are given by straight bars or straps such as 6 and 7 directly connecting the anodes as indicated in dotted and full lines respectively in Fig. 1. The inductance of the inductance loop thus formed will vary with the position of the strap 6 or 7 along the anode. The nearer is the strap, namely as indicated at 7, to the screening grid terminal 4, the smaller will be the loop and thus the inductance, whilst if the straight strap or bar such as 6 is located further from said grid terminal then the greater will be the inductance of the loop thus formed. It will also be possible as indicated at 8 and 9 to have one or more inductance loops such as 8 connected by the straight strap parts 9 to any parts of the anodes.

Referring next to Fig. 2 which indicates one feature of the present invention, in order that the valves may be caused to oscillate at the lowest possible frequency as well as at higher frequencies, each anode is provided with a switch contact face 10 whilst the inductance 11 which may be constituted by a straight bar for minimum wavelength or may have one or more loops therein as indicated in dotted lines at 8, has

contact faces 12 and the gap between each face 10 and 12 is made a minimum but always sufficient to withstand the working voltage stresses between said faces. The gap 13 between said faces is adapted to have inserted in it a movable contact bridge which is not shown in Fig. 2. When said bridge is thus in position the valves will clearly operate at the minimum possible wavelength. When said contact bridge is removed the inductance 11 is no longer in circuit and the anodes can be connected to another inductance and to this end the movable bridge may be in the form of a pivoted or otherwise movable switch arm.

In a particular arrangement illustrated by Figs. 3 and 4 each anode 1 or its preferably integral terminal has pivoted to it at 14 the movable blade or bridge 15, the pivot 14 being at that end of the anode which is remote from the screening grid terminal (not shown in Figs. 3 and 4). Thus when the pivoted switch contact blades or bridges 15 are in the positions shown in Figs. 3 and 4 the inductance strap or bar 11 is connected directly between the lower ends of the anodes. The member 11 is preferably wide in the direction which is parallel with the axis of the inductance loop of which said member 11 forms a part.

By simultaneously swinging the two movable bridge members 15 away from their illustrated positions said movable bridge members may be caused to engage any one of the pairs of jaw or other contacts 16, 17 and 18 (Fig. 4) which are mounted on pillars or on a panel 19 and are connected respectively to inductance coils 29, 21 and 22. The member is shown in dotted lines at 15a as connecting the inductance coil 21 through the inductance terminal contacts 17 to the anodes of the two valves.

At the lower part of Fig. 4 is shown a corresponding wave changing arrangement for the grid circuit, the member 15 in this case being pivoted to the grid terminal 23. For the minimum wavelength the member 15 engages jaws 24 which are connected to the straight inductance strap 11 which extends vertically downwards from the plane of the paper to the other valve, and each jaw is connected to the associated grid terminals for example by the longitudinal member 25.

If the valves are required to operate on a wavelength slightly higher than the minimum wavelength provided by the straight strap 11 at the lower ends of the anodes, the contact terminal members 12 may be extended, as shown in Fig. 5, in the form of parallel bars 26 longitudinally between which is arranged to slide a bar 27, the position of which may be adjusted as will be fully understood, for varying the wavelength more or less above the minimum, when the bridging members such as 15 are between the faces 10 and 12.

Referring lastly to Figs. 6 and 7 which represent a modification of the arrangement shown in Fig. 5, the terminals 28 of a pair of push-pull valves, for instance grid terminals thereof, may have secured to them annular members 29 carrying longitudinal contact faces 30 between which are arranged the straight bar inductance 31 and the inductance 32 having a semi-circular or larger loop. These inductances have contact terminal members 33, 34 so that the bridge 15 may be moved along the contact faces 30 to engage either the inductance terminal member 34 or the inductance terminal member 33 whereby to vary the inductance value to a relatively small extent.

Instead of all the engaging contact faces such as 10, 12 being plane, certain of them may have straight or arcuate knife edges so as to obtain a more efficient high frequency contact in the manner described with respect to Fig. 8 of said Application Serial No. 516,103 filed of even date, herewith, this particular feature being a subsidiary feature of the present invention, but being more particularly claimed in the application just above mentioned.

Reverting to Fig. 3 of the accompanying drawings the parallel lines 35 indicate feeders by which the oscillations from the two valves may be taken away, for instance to a di-pole aerial (not shown). It will be understood, however, that inductive or capacity couplings may be employed alternatively to the conductive coupling illustrated in Fig. 3.

We claim:

- 20 1. A short wave radio transmitter having wave changing arrangements and including a valve having an electrode terminal member, said member having a switch contact face, an inductance including a terminal member having a contact face spaced from said first face only a sufficient distance to withstand the working voltage between said faces, and a movable contact having opposed faces adapted to be brought into and out of engagement with the two first-mentioned contact faces.
- 25 2. A short wave radio transmitter having wave changing arrangements and of the character defined in claim 1, wherein one of each pair of opposed contact faces is provided with a knife edge.
- 30 3. A radio transmitter of the character defined in claim 1, wherein the arrangements are duplicated symmetrically for a pair of push-pull valves and with the inductance between them and including two contact faces, one opposite the contact face of each valve electrode terminal.
- 35 4. A short wave radio transmitter having wave changing arrangements and including a valve having an electrode terminal member, said member having an elongated switch contact face, a plurality of inductances each including a contact face, each of said inductance contact faces being opposite a different longitudinal portion of said elongated contact face and being spaced from the latter only a sufficient distance to withstand the working voltage between said faces, and a movable contact having opposite faces adapted to be brought into and out of engagement with opposed contact faces.
- 40 5. A short wave radio transmitter having wave changing arrangements and of the character defined in claim 4, wherein one of each pair of opposed contact faces is provided with a knife edge.
- 45 6. A radio transmitter of the character defined in claim 4, wherein the arrangements are duplicated symmetrically for a pair of push-pull valves and with the inductance between them and including two contact faces, one opposite the elongated contact face of each valve electrode terminal.
- 50 7. A short wave radio transmitter having wave changing arrangements and including a valve having an electrode terminal member, said member having a plurality of spaced contact faces, a plurality of inductances each including a contact face, each of said inductance contact faces being opposite one of said first-mentioned contact faces and being spaced from the latter only a sufficient distance to withstand the working voltage between said faces, and a movable con-

tact having opposite faces adapted to be brought into and out of engagement with opposed contact faces.

8. A short wave radio transmitter having wave changing arrangements and of the character defined in claim 7, wherein one of each pair of opposed contact faces is provided with a knife edge.

9. A radio transmitter of the character defined in claim 7, wherein the arrangements are duplicated symmetrically for a pair of push-pull valves and with the inductance between them and having two contact faces, one opposite a contact face of each valve electrode terminal.

10. A short wave radio transmitter having wave changing arrangements and including a pair of valves each having an electrode terminal member, each of said members being provided with a switch contact face, which two faces are opposed, an inductance between said faces comprising a pair of spaced conductors and a bar slidable upon and between said conductors, each of said conductors including a face to oppose a valve terminal member face, a movable contact including two bars, each of said bars including opposed faces adapted to be brought into contact with the face on one of said conductors and the opposed face of a valve electrode terminal.

11. A short wave radio transmitter of the character defined in claim 10, wherein said movable contact is pivoted and other inductances are positioned in its path of movement.

12. A short wave radio transmitter having wave changing arrangements and including a valve having an elongated electrode terminal member, said member having a switch contact face, an inductance including a terminal member having a contact face spaced from said other face only a sufficient distance to withstand the working voltage between said faces, a wave changing contact element pivoted upon said electrode terminal at a point remote from the position for minimum wave length, said contact element having a length substantially corresponding to the length of the contact face of said

electrode terminal member, and a straight bar inductance including a contact face positioned to be engaged by said contact element when the latter is in the minimum wave length position.

13. A short wave radio transmitter having wave changing arrangements and including a valve having an elongated electrode terminal member, said member having a switch contact face, an inductance including a terminal member having a contact face spaced from said other face only a sufficient distance to withstand the working voltage between said faces, a wave changing contact element pivoted upon said electrode terminal at a point remote from the position for minimum wave length, said contact element having a length substantially corresponding to the length of the contact face of said electrode terminal member, a straight bar inductance including a contact face positioned to be engaged by said contact element when the latter is in the minimum wave length position, and a plurality of inductances each including a contact face adapted to be selectively engaged by said contact element in other positions of the latter to thereby change the wave length.
